DESIGN FOR A BRIM FOR A HELMET

Frederick R. Wulsin, Providence, R. I.

Application January 14, 1943, Serial No. 109,261

Term of patent 7 years

To all whom it may concern:

Be it known that I, Frederick R. Wulsin, a citizen of the United States, residing at Providence, Rhode Island, have invented a new, original, and ornamental Design for a Brim for a Helmet, of which the following is a specification, reference being had to the accompanying drawing, forming part thereof.

Fig. 1 is a plan view of a brim for a helmet, showing my new design, and

Fig. 2 is a side elevational view thereof.

I claim:

The ornamental design for a brim for a helmet, as shown.

FREDERICK R. WULSIN.
